UNITED STATES PATENT OFFICE.

ARCHIBALD S. B. LITTLE, OF SPRINGFIELD, ILLINOIS, AND ROBERT M. FEUSTEL, OF MADISON, WISCONSIN.

STREET-INDICATOR.

1,155,587.

Specification of Letters Patent.

Patented Oct. 5, 1915.

Application filed December 31, 1914. Serial No. 879,866.

To all whom it may concern:

Be it known that we, ARCHIBALD S. B. LITTLE and ROBERT M. FEUSTEL, citizens of the United States, residing, respectively, at 5 Springfield, in the county of Sangamon, State of Illinois, and at Madison, in the county of Dane, State of Wisconsin, have invented certain new and useful Improvements in Street-Indicators, of which the 10 following is a full, clear, and exact description, reference being had to the accompanying drawings, forming a part hereof.

Our invention has relation to improvements in street indicators for passenger (or 15 other) cars; and it consists in the novel features of construction more fully set forth in the specifications and pointed out in the claims.

In the drawings, Figure 1 is a front face 20 elevation of the indicator box or casing with reducing gear casing attached; Fig. 2 is a top plan of the left-hand end of Fig. 1, the casing of the reducing gear being in section; Fig. 3 is an enlarged vertical longitudinal section through the casing or box of the reducing gear, on the line 3—3 of Fig. 2; Fig. 4 is a top plan of the indicator box, with parts broken away to expose the interior thereof; Fig. 5 is a vertical longitudinal section on the zig-zag line 5—5 of Fig. 4; Fig. 6 is a vertical cross-section on the line 6—6 of Fig. 1; Fig. 7 is a vertical cross-section on the line 7—7 of Fig. 1, the box being broken in the middle; Fig. 8 is 30 a vertical cross-sectional detail on the line 8—8 of Fig. 5, showing the direction indicator; Fig. 9 is a top plan of the lower web-guide or apron; Fig. 10 is a front elevation of the web-guide partly broken away; Fig. 11 is a vertical cross-section on the zig-zag line 11—11 of Fig. 10; and Fig. 12 is a diagrammatic illustration of the slot in the web showing its relation to the web-advancing disk or wheel.

The present invention is directed to improvements in street indicators for railway cars generally, and street cars in particular, having for its object to provide an indicator which may be applied to a car 45 however propelled. It may be applied for example to cars propelled electrically, by steam, air, gas, or by draft animals, the reason therefor being that the mechanism of the indicator is independent of the motive

power, deriving as it does, its power from 55 the rail along which the car travels.

A further object is to provide an indicator presenting a wide range of information; one which is positive in action; one which is reliable; one readily applied to existing cars; 60 one in which any error is readily corrected; one susceptible of many modifications in construction without a departure from the basic principle of its operation, or from the spirit or nature of the invention; and one 65 possessing further and other advantages, better apparent from a detailed description of the invention which is as follows.

Referring to the drawings, 20 represents a shaft to which rotation is imparted in any 70 suitable way by the travel of the car, said shaft terminating in a bevel pinion 21 meshing with a similar pinion 22 at the outer end of a shaft 23 forming one of the members of suitable reducing gears confined in the 75 box or casing 28, the said shaft being mounted on ball bearings at the bottom of said box, and carrying a pinion 29 adjacent one of the walls of the box, said pinion meshing with a gear wheel 30 on a parallel worm-shaft 31, the worm pinion 32 whereof meshes with a worm gear 33 in the box, the gear 33 being mounted on a shaft 34 projecting with one end through the box wall, as fully shown in Fig. 2. We do not of 80 course wish to be limited to this special form or construction of reducing gear, any equivalent thereof answering our purpose.

Bolted, or otherwise secured to the shaft 34, so as to form an extension therefor, is 90 the clutch-shaft 35 mounted between, and extending through one of, two opposite walls of the indicator casing or box 36, said shaft having mounted thereon within the casing 36, the opposing bevel pinions 37, 37', (Fig. 95 6) which are in mesh at points diametrically opposite one another with a bevel gear wheel 38 at one end of a counter-shaft 39 disposed at right angles to the clutch-shaft 35 and mounted in bearings or standards 40, 100 40, at the bottom of the indicator box 36, the farther end of the shaft terminating in a bevel pinion 41 (Fig. 5).

Formed with the pinions 37, 37', respectively, are the female clutch-sections or 105 members *t*, *t'*, with which is adapted to alternatively coöperate the adjacent portion of a sliding double-male member *m* which is

slidingly feathered to the shaft 35 as well understood in the art, so that with a rotation of the shaft 35 in a given direction, when the male *m* is shifted into engagement with 5 the female *t* of the pinion 37, rotation in a given direction will be imparted to the gear 38 and its shaft 39; and when the male is shifted to engage the female *t'* of the pinion 37', rotation will be imparted to the 10 gear 38 and its shaft 39 in the opposite direction. When the member *m* is shifted to an intermediate point on the shaft 35 so as to engage neither member *t* or *t'*, no rotation will be imparted to the shaft 39.

15 The mechanism for shifting the clutch member *m* is as follows: Disposed in a transverse bottom trough or basin *E* of the box 36 is a screw-shaft 42, one end of which is provided with a square or polygonal terminal *w* extending outside the box, said square end receiving the socket of a suitable detachable crank handle *A* by which rotation may be imparted to the screw-shaft in either direction, said direction depending on 20 whether the car is inbound or outbound. A direction indicator *r* marked with the words "In" and "Out" (Fig. 1) serves to guide the operator in determining the direction he shall turn the crank *A* to effect a shifting 25 of the member *m* to cause it to engage one or the other of the female sections *t*, *t'*. The shaft 42 is provided with a screw or threaded portion 43 which is traversed by the interiorly screw-threaded terminal of the 30 lower arm of a clutch-shifting member 44, said shifter member being formed with an intermediate hub portion or enlargement *i* fitting loosely on a guide rod 45 mounted in the box 36, the hub being limited by pins 35 or pegs 46 on the rod, in its reciprocating movements (Fig. 6). The free end of the upper arm of the clutch shifter 44 terminates in the usual fork *f* for spanning the groove of the male member *m*. It will be 40 readily seen from the connections described, that with a turn of the crank *A* and shaft 42 in one direction, the shifter 44 will be caused to travel in a given direction so as to shift the member *m* into engagement with 45 one of the female members *t*, *t'*, and with a turn of the crank in the opposite direction, the shifter will travel in the opposite direction, thereby causing the member *m* to engage the opposite female clutch member, the 50 shaft 39 being caused to rotate in one direction or the other, depending on which female clutch member is engaged. When the member *m* stands out of engagement with both members *t*, *t'*, no rotation is imparted 55 to the shaft 39, the hubs of the pinions 37, 37', being loose on the clutch-shaft 35, thus allowing the clutch shaft to rotate without affecting the gear 38. Obviously, from the manner of their mounting (Fig. 6) the loose pinions 37, 37', are held against longitudinal 60

displacement on the shaft 35 so that they remain permanently in mesh with the gear 38.

65 Meshing with the pinion 41 on the counter-shaft 39 is a bevel pinion 47 secured to the centrally disposed vertical web-driving shaft *S* mounted in the indicator box or casing 36, said shaft having secured thereto, suitable disks or wheels 48, 48, which are provided with radially disposed peripheral teeth or pins 49 meshing with properly spaced openings or holes *u* distributed along the web or indicator sheet 50 on which the names of the streets (and advertising matter if desired) are printed, the web traveling 70 horizontally across the casing 36, and having the necessary section thereof exposed through a glass plate *G* in the front wall of the casing. The glass carries an arrow *D* which is marked directly over the name of 75 the street which the car is about to cross, or which the car has reached, the name of at least one street which the car has already passed and which it is next to cross being likewise indicated and exposed through the 80 glass window *G*. Thus in Fig. 1, the street which the car is crossing or is about to cross is indicated by the arrow *D*; and assuming that the web 50 is traveling to the left, it shows that 2nd street has been passed and 85 that 4th street is the next to be crossed. If the web travels to the right then it is 4th street which has been passed, and 2nd street the next to be crossed, 3rd street being the 90 street the car is crossing. The web also indicates the street on which the car is traveling. Thus in Fig. 1 the web shows the car to be traveling "on Main Street." Should the car pass to another street, the web would 95 indicate that fact. As shown in Fig. 1, the web has marked thereon suitable instructions, as for example "Transfer to Market" 100 indicating that a passenger shall transfer to Market on the corner of Main and 2nd streets. It may also indicate other directions (on the order of advertisements) such as "Theatre 7:30 and 9:30", "Music Store", 105 showing that the theater and music store are to be found on the corners of the streets where marked on the web. 110

115 To indicate when the clutch member *m* is in proper engagement to correspond with the in-bound trip of the car, we secure to the interiorly threaded end of the member 44 traversing the screw-shaft 42, a pin 51 terminating in a head 52 (Figs. 5, 8), the pin traversing a slot *s* formed in the inner wall of the trough or basin *E*, said pin co-operating with an indicator *I* marked on a plate 53 secured to the trough wall, said indicator having marked thereon the words "In", "Out", and "N", corresponding respectively to the notations "in", "out" and the clutch arrow on the indicator *r* (Fig. 1) 120 which instructs the operator in which direction 125 the car is traveling. 130

tion he is to turn the crank A to bring the clutch member *m* into engagement with one or the other of females *t*, *t'*, or to bring it into an intermediate or neutral (N) position so as to disengage it from both females. The indicator I is therefore a check on the indicator *r*. In other words, when the operator turns the crank A (Fig. 1) clockwise or toward the notation "in", as pointed by the arrow, the shaft 42 will be turned in proper direction to shift the clutch member *m* to the right (Fig. 6) so as to cause it to engage the female member *t'* on the pinion 37', whereby the gear 38 and its shaft 39 are turned in proper direction to advance the web 50 in a direction corresponding to the inbound trip of the car. When the crank A is turned counter-clockwise the reverse of these operations takes place, the member *m* being shifted to engage the female *t* on the pinion 37, so that the web 50 is advanced in the opposite direction. When the members *m*, *t'*, are in engagement, the head 52 of the pin 51 will be opposite the "in" mark on the indicator I, and when the members *m*, *t*, are engaged, the head 52 will be opposite the "out" mark on said dial, the pin head coming opposite the "N" or neutral mark when the member *m* is disengaged from both of the clutch members *t*, *t'*.

It is of course essential that during the advances of the web 50, the same should be properly guided and for that purpose we make the following provision: Disposed opposite the front wall of the indicator box 36 in front of each web-actuating wheel 48 is a sheet metal apron or plate 54, having an outwardly bent portion 55 terminating in a vertical flange 56 through which the plate 40 is fastened to the said front wall of the box (Figs. 4, 7). The apron 54 has a rear vertical fold *x* folded close to the apron and extending substantially to the base thereof, the member *x* having a parallel folded member *y* spaced a suitable distance however from the member *x* whereby there is formed a deep narrow passage-way *p* for the free travel of a considerable marginal section of the web (Fig. 11) as the latter is advanced across the window opening of the indicator box. Preferably, the web is engaged by the pins 49 in its passage through the passage or guide-way *p*, and to permit the pins to reach the web, the members 54 and *x* are provided with elongated registering slots *c*, *c*, of equal width, and the member or fold *y* is provided with a slot *c'* of equal length but somewhat wider (Figs. 10, 11), the wide slot allowing for a free traverse therethrough of the peripheral portion of the disk 48, whereas the joint slot *c*, *c*, allows for the free play therethrough of the pins 49, so that the latter may properly engage the holes *u* to actuate the web. The web is additionally guided by the vertical rollers

57, 58, suitably mounted in the box 36 on opposite sides of the shaft S, the purpose of the apron being more to offer a proper support and guide for the web as it is seized and advanced by the radial pins or teeth 49 of the disks 48. The ends of the web are secured to hard wood winding rollers 59, 59', respectively, the former being mounted on a shaft 60 and the latter on a shaft 60'. One end of the shaft 60 terminates in a square end *w'* for applying a crank handle A, a like square end *w''* terminating the shaft S and for a like purpose (Fig. 1).

In its advances, the web 50 of course should be maintained taut so as to wind and unwind positively, and that it may present an unwrinkled surface to the eye of the reader. Proper tension is therefore permanently exerted on the web for this purpose by the following mechanism: Disposed adjacent to the winding roller 59, on the bottom of the box 36 is a flanged cup 61, the flange being formed with a slit 62 through which is passed the outer end of a coiled spring 63, the end of the spring being bent against the outer wall of the flange (Fig. 4) whereby it is made fast to the cup. The inner end of the spring is fastened to an arbor or spindle 64 supported at the upper end in a bracket 65 and at its lower end in the bottom socket of the cup (Fig. 5) whereby upon winding up of the spring, rotation is imparted to the arbor, the same as in ordinary clock mechanism. The spindle 64 carries a gear wheel 66 which meshes with a pinion 67 on the shaft (60) of the roller (59). When the spring is under tension it will tend to rotate the arbor or spindle 64 and its gear wheel 66, and hence tend to impart rotation to the pinion 67 and the shaft of the winding roller. A corresponding cup 61', spring 63', spindle arbor 64', gear wheel 66', pinion 67', is installed in connection with the shaft 60' of the roller 59' (Fig. 5). When the web 50 is advanced in a direction to unwind from a roller (59, 59') it rotates that roller in a direction to cause the spring to wind up, the opposite roller or that on which the web is wound being rotated in a direction to unwind its spring. This tends to impose an increasing tension on the spring connected with the unwinding roller, and a decreasing tension on the spring connected with the winding roller. It follows that when the quantity of web on one roller is equal substantially to that on the opposite roller, the tensions of the springs will be equalized, but from that moment, and with the farther advance of the web, one spring will begin to increase in tension while the other will begin to decrease. The tension of the spring identified with the roller from which the web has been practically unwound will assist in the driving of the web when the direction of advance

of the latter has been reversed; but while that is true, the springs 63, 63', are not relied on for driving the web, that being accomplished by the disks 48, 48. The functions of the springs are to maintain the web taut, the tension of one spring being always opposed to that of the opposite spring, the tendency of either spring being always to unwind or uncoil and hence exert a draft 10 on the web, by tending to rotate the rollers in opposite directions.

To automatically arrest any advance of the web when the latter has been practically unwound from its winding roller, we provide 15 the web in the path of the pins 49 of the disks 48, with elongated slots s', s', so that with any rotation of the disks 48 the pins will simply play through the slots s' without engaging the web and the latter 20 comes to a dead stop (Fig. 12). Of course in order to bring the slots to the position indicated, a pin 49 must first engage the nearest terminal of the slot so as to effect a final advance in the web, the movement of 25 the web in such final advance bringing the end of the slot thus engaged out of range of succeeding pins, thereby allowing the disks to continue in their rotations without affecting the web.

30 The operation will be clearly apparent from the foregoing description but may be briefly summarized as follows: If the car is to make an out-bound trip, the conductor or operator seizes a crank-handle such as A, 35 applying it to the screw-shaft 42 and turns the shaft counter-clockwise (Fig. 1) until the male clutch member m has engaged the female member t, that fact being indicated by the head 52 of the pin 51 coming opposite 40 the "out" notation on the check indicator I, (Fig. 8). With a travel of the car as indicated, we can assume that the direction of rotation imparted to the gear 38 and hence to the countershaft 39 is as indicated by the 45 arrow in Fig. 6. This will impart rotation to the shaft S in a direction to exert a draft on the web 50 so as to advance it to the right (Figs. 4, 5), that is to say, it will pull the web off or unwind the same from, the roller 50 or reel 59 and cause it to wind on the roller 59', being facilitated by the tension of the spring 63' which as previously explained always tends to unwind and hence exerts a tension on the web. At the same time, the draft 55 on the web 50 by the pins 49 of the disks 48 secured to the shaft S will cause the roller 59 to rotate in proper direction to wind up the spring 63, and thus progressively increase its tension. This increasing tension 60 on the roller which is being constantly stripped of its web is desirable, because with a constantly decreasing quantity of web the roller is becoming lighter and hence more readily turned; and to maintain as nearly 65 as possible a constancy of resistance to the

draft on the web, what the roller loses in weight it keeps gaining (in the matter of resistance) by a corresponding increase in the tension of the spring. The opposite roller (59') on the other hand is increasing in 70 cross-sectional diameter by reason of a constant accession of web material to its periphery so that a correspondingly increasing sweep of said periphery results from the same angular rotation of the roller. This increased peripheral travel tends to exert a draft on the section of web which is being wound on the roller, because it tends to wrap or take up a greater length of web than is unwound from the roller 59 whose cross-sectional diameter is constantly decreasing. It is for this reason therefore that the winding of the spring 63 (63') is brought about by the unwinding or unwrapping of the web 75 from its roller, the web being at all times kept taut by the action of the springs which tend to unwind. The web of course is actuated by the pins 49 on the disks 48 (a single roller or cylinder or its equivalent could obviously be substituted for the two disks 48), 80 the shaft S of which derives its rotation from the clutch-shaft 35 which in turn is rotated by the shaft 34 of the reduction gearing operated from the flexible shaft 20. If the car is in-bound instead of out-bound, 85 the operator shifts the male clutch member m to engage the female t', whereupon the shaft S will rotate in the opposite direction, and the web will travel in the opposite direction; and what was previously the unwinding roller (59) will now become the winding roller, the roller 59' becoming the unwinding roller. Should the web be carried beyond its normal range of travel it will come 90 to a dead stop the moment the pins 49 come opposite the slots s', s', of the web as already explained. To bring the web back to proper position, the operator moves the clutch member m to central or neutral position so as to be disengaged from both females t, t', thus leaving the shaft 39 operatively disconnected from the clutch-shaft, 95 and by applying the crank-handle A to the square end w' of the shaft 60 of the roller 59 he can turn the roller the necessary degree to right the web. So too, should the web 50 at any time while in service, be at variance or out of register with the streets which it should indicate, so that the names 100 of the streets exposed through the glass G 105 no longer correspond with the actual streets the car is traversing or crossing, the error can be rectified or corrected by the operator or conductor applying the crank-handle A to the square end w'' of the shaft S, and giving the shaft a sufficient turn or turns to 110 bring the web to its true or corrected position, it being understood of course that before that is done, the male clutch member m 115 is shifted to central or neutral position in 120 125 130

order to disengage the shaft 39 from the clutch-shaft 35.

It is apparent from the foregoing that the details of the mechanism may be departed from in many particulars without a departure from either the spirit or nature of our invention. Features shown but not alluded to are well understood in the art and require no description in the present connection.

We do not wish to limit the invention for indicating "streets" merely, as it may be used to indicate stations, or stopping points for steam or interurban cars; and the term "street" is not to be regarded as a limitation in any way, the same being herein used for convenience of title. Neither do we wish to restrict the indicator member to a "web" specifically.

Having described our invention, what we claim is:

1. In an indicator of the character described, a traveling web provided with a series of alining perforations and elongated slots, a rotating member provided with peripheral radially disposed pins or teeth for engaging the perforations for advancing the web, and operating through the slots without exerting an advance on the web, as set forth.

2. In an indicator of the character described, a traveling web, a guide therefor comprising a member provided with a deep narrow passage for the traverse of a marginal section of the web, an actuating disk or wheel, peripheral radially disposed pins, the walls of the guide and passage thereof aforesaid being provided with elongated registering slots for the traverse of the pins and peripheral portion of the disk or wheel, the web being provided with a series of openings or perforations opposite the slots for the reception of the pins.

3. In an indicator of the character described, a traveling web, means spaced a suitable distance apart for maintaining a given section of the web taut or under tension, a guiding member interposed between said means provided with a narrow passage for receiving a marginal section of the web, an actuating disk, peripheral radially disposed pins on the disk, the walls of the pas-

sage aforesaid being provided with elongated slots for accommodating the pins aforesaid, the web being provided with perforations opposite the slots for receiving the pins of the actuating disk.

4. In an indicator of the character described, a clutch-shaft, a sliding clutch-member on the shaft, a screw-shaft, a detachable crank-handle for operating the screw-shaft, a sliding clutch member on the clutch-shaft, a clutch-shifter on the screw-shaft, an indicator for indicating the direction of rotation of the screw-shaft to shift the clutch member in a given direction, a second indicator serving as a check on the first indicator, and a member on the clutch-shifter coöperating with said second indicator, for the purpose set forth.

5. In an indicator of the character described, a traveling web, means spaced a suitable distance apart for maintaining a given section of the web taut or under tension, a guiding member interposed between said means provided with a narrow passage for receiving a marginal section of the web, a rotary actuating member, radially disposed pins on said member, the walls of the passage aforesaid being provided with slots for accommodating the pins aforesaid, the web being provided with perforations opposite the slots for receiving the pins of the actuating member.

6. In an indicator of the character described, a traveling web, means spaced a suitable distance apart for maintaining a given section of the web taut or under tension, a perforated guiding member interposed between said means and engaged by the marginal portion of the web, a rotary actuating member, radial pins on said member operating through the perforations of the guiding member, the web being provided with perforations opposite the perforations of the guiding member for receiving the pins of the actuating member.

In testimony whereof we affix our signatures, in presence of two witnesses.
